SOUND REPRODUCER

Edwin H. Smythe, Evanston, Ill., assignor to
Western Electric Company, Incorporated, New
York, N. Y., a corporation of New York

Application August 17, 1926. Serial No. 129,734

20 Claims. (Cl. 181—31)

This invention relates to sound reproducers employing large direct-acting diaphragms.

An object of the invention is to reproduce efficiently and faithfully all sounds within the 5 audible range.

Another object of the invention is to increase the energy imparted to the air from a sound radiating surface and to reduce the radiation of out of phase energy.

10 The invention provides a sound reproducer having a transversely rigid and preferably conical diaphragm and an annular transversely rigid and preferably frusto-conical section which are supported solely at their common periphery in 15 such a way that the periphery is constrained with respect to transverse movement and is left free and unconstrained with respect to radial and torsional movement.

Low frequency sound vibrations applied at the 20 apex of the diaphragm cause the periphery to expand and contract, permitting the entire surface of the diaphragm to vibrate in a direction transverse to the plane of its base, and producing a transverse movement of the frusto-conical section in opposite direction to the transverse movement of the diaphragm. As a result of this action, the sound waves transmitted by the outer surface of the frusto-conical section are in phase 25 with the waves of corresponding frequencies transmitted by the outer surface of the conical diaphragm, and the inner surfaces of these members cooperate to produce sound waves in phase opposite to that of the waves produced by the outer surfaces.

30 According to another feature of the invention, a partially enclosed air chamber is provided on each side of the conical diaphragm. The columns of air confined in each air chamber add air mass reactance to the diaphragm, which 35 serves to improve the radiation of energy in the low frequency range.

The invention will be described in detail in connection with the accompanying drawing, in which similar reference characters designate 40 similar parts in the different views, and in which:

Fig. 1 is a side view, partly in section, of a sound reproducer comprising a double cone structure supported at the periphery in accordance with the invention;

Fig. 2 is a front elevation on a reduced scale of the sound reproducer shown in Fig. 1;

Fig. 3 is a fragmentary view illustrating the method of supporting the double cone structure;

Fig. 4 is a side view, partly in section, of a

sound reproducer having a modified form of peripheral support and having a partially enclosed air chamber on both sides of the diaphragm; and

Fig. 5 is a partial cross-sectional view showing a modification of the double air chamber construction.

The sound reproducer shown in Fig. 1 comprises a radiator having a front conical diaphragm 10 and a rear frusto-conical section 11 cemented together base to base. Both portions 65 of the radiator are preferably constructed of light stiff material, such as thin wood veneer or blotting paper. An annular binding strip 12 is disposed about the truncated end of the frusto-conical section 11 for a purpose hereinafter described. 70

The radiator is mounted within an annular trough-like frame 13 preferably comprising two semi-circular portions which may be clamped together by means of bolts 14 after the radiator 75 is placed inside the frame. The device is mounted on a stand 15 having an upright portion 16 to which are bolted diametrically opposite edges of the frame 13.

The cones 10 and 11 are supported at their 80 common periphery by means of taut cords 17 passing through the small holes 18 in the depending rims of the frame 13. The cords 17 may be laced back and forth through the holes 18, as is more clearly shown in Figs. 2 and 3, the 85 common peripheral edge of the cones being fastened to the cords by means of cement 19. A supporting member 20 mounted on the upright 16 carries the receiver unit 21 for actuating the diaphragm 10. The member 22 is provided for 90 connecting the driving stem of the receiver unit to the apex of the diaphragm. The receiver unit 21 may be of the type disclosed and claimed in U. S. Patent 1,709,571, granted April 16, 1929 to H. C. Harrison. 95

In the construction described above the periphery of the double cone structure is constrained in a transverse direction by means of the cords 17, but is left free to move radially and torsionally. This construction reduces the opposition due to extensional and compressional forces in the front and rear cones, and gives free play to any tendency toward peripheral expansion and contraction at the periphery as the diaphragm vibrates. As the outer edge expands 105 and contracts radially and peripherally as a result of the driving force applied at the apex, this expansion and contraction produce a transverse movement of the rear frusto-conical section 11 in opposite direction to the transverse movement 110

of the conical diaphragm 10. Pressure waves which are produced by the frusto-conical section 11 are therefore in phase with the waves of corresponding frequencies produced by the diaphragm 10. This particular action occurs in the low frequency range where it increases and emphasizes the pulsating or pumping action in the enclosed air space between the front and rear cones. This has the effect of increasing the air transformer action and the effective air mass reactance upon the rear surface of the diaphragm 10 and improving the response in the low frequency part of the scale.

The truncated end of the frusto-conical section 11 is left unsupported and free to vibrate, the sole support being at the common peripheral edge of the double cone structure. The binding strip 12 disposed around the truncated edge of the frusto-conical section 11 is primarily to give circular rigidity, and to provide stiffening of the inner edge to resist the radially inwardly and outwardly moving forces caused by the peripheral expansion and contraction, and thus make these forces effective in producing the transverse movement of the frusto-conical section 11. By giving this stiffening ring the proper value of stiffness with respect to its mass, it is possible to exercise control over the part of the frequency scale at which the pumping action of the frusto-conical section will be made effective.

The modification of the invention shown in Fig. 4 includes a stationary supporting wall 23 in the form of a truncated cone which is mounted at its small and in the annular member 24 in any suitable manner. Since the mass of this stationary wall is unimportant, it may be made entirely of metal, heavy cardboard or the like. The peripheral support for the sound radiator comprises a ring 25 of light flexible material, such as very light gauge duralumin or light stiff paper, which as shown may be made integral with the stationary wall 23 or may be attached thereto in any suitable manner. The ring 25 is transversely slotted to provide a plurality of tongues 26 which offer very slight resistance to the radially acting forces developed in the conical diaphragm 10, and at the same time offer a large resistance to transverse movement. The common periphery of the conical diaphragm 10 and the frusto-conical section 11 is seated in the upturned ends 27 of the flexible tongues 26.

In this construction, openings are provided on both sides of the conical diaphragm at 12 and 24, respectively, the frusto-conical section 11 and the stationary wall 23 providing partially enclosed air chambers on both sides of the diaphragm. The air enclosed in these chambers is found to add air mass reactance to the diaphragm, which tends to lower its fundamental frequency and hence improves the performance in the low frequency range. Since it is desired in this construction to secure the maximum air transformer action on both surfaces of the conical diaphragm, a ribbon of light cloth 28 is pasted over the peripheral supporting ring 25 in such a way as to cover the slots formed by the tongues 26 without preventing the tongues from yielding to the radial movements of the diaphragm. The cloth covering 28 is to prevent air leakage through the peripheral supporting ring.

Fig. 5 shows a modification of the double air chamber construction of Fig. 4. The edges of the section 11 and the wall 23 are bent outwardly to form flanges 29. The periphery of the diaphragm 10 is supported between loosely packed

sheets of paper 30 which are confined in the space between the flanges 29 and held together by means of the clamping ring 31. This provides a convenient construction for damping the periphery of the diaphragm 10.

The invention is also capable of many other modifications and adaptations without departing from the scope and spirit of the invention as defined in the appended claims.

What is claimed is:

1. A sound reproducer comprising a large direct acting diaphragm having a configuration to impart to it inherent stiffness from the center outwardly, and means for constraining the edge of said diaphragm with respect to transverse movements, said means exercising substantially no constraint to movements of said diaphragm edge in a radial direction. 90

2. A sound reproducer comprising a conical diaphragm driven at the apex, and means for constraining said diaphragm in a direction perpendicular to the plane of its base the periphery of which may move substantially freely in a direction along said plane. 95

3. A sound reproducer comprising a conical diaphragm driven at the apex, and a support for the base of said diaphragm including a plurality of flexible members maintaining said base in one plane, said members imposing substantially no restraint to the expansion and contraction of the base in response to sound vibrations. 100

4. A sound reproducer comprising a conical diaphragm driven at the apex, and a support for the base of said diaphragm including a plurality of circularly disposed members which are flexible only in a direction of the plane of said base. 110

5. A sound reproducer comprising a conical diaphragm and a frusto-conical section having their bases joined together to form a common periphery, and means for constraining said periphery with respect to transverse movement, said means exercising substantially no restraint to the free movement of said periphery in a radial direction. 115

6. A sound reproducer comprising a conical diaphragm and a frusto-conical section bound together along an edge, and a support for said bound edge including a plurality of flexible members maintaining said edge in one plane, said support exercising substantially no restraint to the expansion and contraction of said bound edge in response to sound vibrations. 120

7. A sound reproducer comprising a conical diaphragm driven at the apex, a frusto-conical section having its base joined to the base of said diaphragm, and a flexible support for said diaphragm and said frusto-conical section, said support constraining said joined bases to movement in one plane to cause said frusto-conical section to move in an opposite direction to that of said diaphragm in response to sound vibrations. 125

8. A sound reproducer comprising a conical diaphragm and a frusto-conical section having their bases joined together to form a common periphery, means for driving said conical diaphragm at the apex, and a support for said periphery including a plurality of circularly disposed members which are inherently flexible in a direction of the plane of said periphery and are inherently rigid in a direction perpendicular to the plane of said periphery. 130

9. A sound reproducer comprising a large direct acting diaphragm, and means providing a partially enclosed air chamber on both sides of said diaphragm, the area of the opening of each cham- 135

ber being smaller than the radiating area of the diaphragm.

10. A sound reproducer comprising a conical diaphragm, a frusto-conical support forming a partially enclosed air chamber on one side of said diaphragm, and a frusto-conical section forming a partially enclosed air chamber on the other side of said diaphragm.

11. A sound reproducer comprising a conical diaphragm driven at the apex, a frusto-conical section forming a partially enclosed air chamber on one side of said diaphragm, a stationary frusto-conical support forming a partially enclosed air chamber on the other side of said diaphragm, and means for flexibly connecting said diaphragm and frusto-conical section to said support.

12. A sound reproducer comprising a conical diaphragm driven at the apex, a frusto-conical section attached to and forming a partially enclosed air chamber on one side of said diaphragm, a stationary frusto-conical support forming a partially enclosed air chamber on the other side of said diaphragm, and means for connecting said diaphragm and frusto-conical section to said support including a plurality of circularly disposed members which are inherently flexible only in a direction of the plane of the base of said diaphragm.

13. A sound reproducer comprising a large direct acting diaphragm having a configuration to impart to it inherent stiffness from the center outwardly, and means to maintain the edge of said diaphragm against movement transverse to the plane of said edge, said means imposing substantially no restraint to the movement of said edge in the plane of the periphery.

14. A sound reproducer comprising a large direct acting diaphragm having a configuration to impart to it inherent stiffness from the center outwardly, and means to allow of a minimum of movement of the edge of said diaphragm in a direction transverse to the plane of its base, said

45

means offering a minimum of restraint to the movement of said edge in the plane of the said diaphragm's base.

15. A loud speaker comprising a supporting member, a housing carried by said supporting member, an actuating device positioned within said housing, a cone shaped diaphragm actuated by said actuating device, and a horn carried by said housing and conforming to the shape of said cone shaped diaphragm for providing a chamber between the exterior surface of said cone shaped diaphragm and the interior wall of said horn.

16. A sound reproducing device comprising a large size diaphragm inherently weakening the higher harmonics, and an air obstruction wall opposite said diaphragm to form an outwardly flaring air chamber for accentuation of said higher harmonics.

17. A loud-speaking device comprising a large size cone-shaped diaphragm, and an air obstruction wall opposite said diaphragm to form an outwardly flaring sound air chamber.

18. In combination with an electric loudspeaker, a loudspeaker actuating element, a cone-shaped sound producing surface operated by said element, and a sound amplifying chamber associated with said cone-shaped surface to form a tapering opening towards the apex of said cone.

19. A loud speaker including a base, a strut extending from the base, a diaphragm mounting means supported by the strut, a diaphragm mounted on the mounting means, and a sound reproducing unit connected to the diaphragm for applying vibrations thereon, and means forming a loading chamber for applying an air column load on the diaphragm.

20. A sound reproducer comprising a direct-acting diaphragm, and means including a frusto-conical member providing a partially enclosed air chamber on each side of said diaphragm, the larger base of said member abutting on the periphery of said diaphragm.
